INVENTOR.

ANDREW S. BROWN.

BY

Richard D. Owen
ATTORNEY.

UNITED STATES PATENT OFFICE.

ANDREW S. BROWN, OF HOBOKEN, NEW JERSEY.

COLLAR OR CUFF BUTTON.

Application filed June 1, 1925. Serial No. 34,204.

This invention relates to collar or cuff buttons and has for its object to produce a novel and improved construction which may be quickly and easily inserted in the button-holes of the shirt band and collar or the cuff to retain the same in their proper condition.

Another object of my invention is to produce a collar button preferably constructed of metal or other equivalent, resilient material, which is very strong and durable, extremely simple in construction, highly efficient in operation and use, practical, and otherwise capable of being manufactured at a low cost whereby its commercial possibilities are greatly enhanced.

To enable others skilled in the art to fully comprehend the underlying features of my invention that they may embody the same in the various modifications in structure and relation contemplated, drawings depicting a preferred form have been annexed as a part of this disclosure and in such drawings, similar reference characters designate corresponding parts throughout all the views, of which,

Figure 1 is a perspective view showing one form of the collar or cuff button.

Figure 2 is a similar view with the head standing substantially at right angles to the base or outer head of the button.

Figure 3 is a view through the button showing the inner head in dotted line position.

Figure 4 is a modified form of the invention.

Referring now to the drawings wherein like reference characters designate corresponding parts throughout the several views, 5 designates the outer head or base of the button, preferably constructed of resilient metal and as shown, is rectangular in formation but may be of any other desired shape as manufacturing necessities and demand may require. The material of the outer head or base is bent on itself as indicated at 6, 7, and then upwardly as indicated by numerals 8 and 9, substantially at right angles to the outer head or base, above referred to. The members 8, 9, constitute what may be termed the shank of the button, and as shown in their normal positions, said members are separated or flared outwardly near their upper end. The material of the button, or in other words, the metal is struck out between the upwardly, extending por-

tions or the shanks and the top portion of the base, forming the cammed surfaces 10 for a purpose presently to appear.

The inner head of the button consists of a somewhat elliptical plate 11 of metal, bent inwardly upon itself as at 12 and then spaced sufficiently from the top 11 thereof so that it may be passed through the openings 13 of the shank as clearly shown by Figures 1 and 3 of the drawings. The free end 14 and the bottom portion 15 of said plate is locked within the bent end 16, which completes the assembly of the base and the inner head above referred to.

It will be understood that due to the resiliency of the material of the inner head as well as the shank, that as the inner head is moved downward, for instance, to the dotted line position, as shown in Figure 3, either to the left or to the right, there will be a slight pressure exerted on either the members 8 or 9 so that they are urged slightly toward each other and in contiguous relation, as shown by Figure 2, in which position, the inner head 11 is permitted to lie substantially at right angles to the outer head or base as said inner head rides upwardly on the cam surfaces 10. On the other hand, when the inner head is moved from the vertical to the horizontal position, the pressure on the member 8 or 9 is thus released, in which instance, the upper ends thereof spread apart, permitting the said head to lie in the horizontal or locked position, when inserted through the button-hole.

In the form of the invention as shown by Figure 4, the inner head 17 is formed similarly to the head 11, described in connection with Figures 1 to 3 inclusive, but it will be observed that in this form of the invention, I dispense with the cam surfaces 10, permitting the free rotation of the said head 17 through the slot or opening 18 of the shank. In this form of the invention, the base 19 is also bent inwardly on itself and then upwardly, forming the shanks 20, 21. In this form of the invention, however, it will be immediately recognized that the resiliency of the metal and particularly the shanks, permits the slight movement of the said shanks toward each other and the inner head is moved to the vertical position and on the other hand, when the said inner head is in the horizontal position, the pressure is

released on said shanks to move outwardly or space apart as shown by Figure 1 of the drawings.

While I have illustrated and described my invention with some degree of particularity, I realize that in practice various alterations therein may be made. I therefore reserve the right and privilege of changing the form of the details of construction or otherwise 10 altering the arrangement of the correlated parts without departing from the spirit of the invention or the scope of the appended claims.

Having thus described my invention, what 15 I claim as new and desire to secure by United States Letters Patent is:—

1. A collar or cuff button of the class described comprising a base bent upon itself and then at right angles forming a pair of 20 substantially parallel, flat shanks, said shanks having an opening therethrough, and a head resiliently locked to the top of said shanks and movable to a horizontal or vertical position relative to the base, and means 25 for raising the head on the shank when said head is moved to vertical position.

2. A collar or cuff button of the class described comprising a base bent upon itself and then at right angles forming a pair of 30 substantially parallel flat shanks spaced slightly at their upper ends, said shanks having an opening therethrough formed by punching lips out of said shanks, an inner head locked to the shanks and adapted to 35 expand and contract the same when moved

from a horizontal to a vertical position relative to the base, and said lips arranged to strengthen said shanks.

3. A collar or cuff button of the class described comprising a base bent upon itself 40 and then at right angles thereto forming a pair of substantially flat, parallel resilient shanks slightly spaced at their upper ends, said shanks having an opening therethrough, an inner head extending through the said 45 opening and above the top of the said shanks and locked thereto, said head being movable to a vertical and horizontal position relative to the base and adapted to expand and contract the said shanks and to lock the said 50 head in its different positions, and cam members on said shank for forcing said head into locking position.

4. A collar or cuff button of the class described comprising a base bent upon itself 55 and then at right angles thereto forming a pair of substantially flat, parallel shanks slightly spaced at their upper ends, said shanks having a square opening therethrough formed by outstruck lips constituting a cam surface on said base adjacent the openings, an inner head passing through 60 said openings and above the top of the shanks and locked thereto, said head being movable over the cam surface whereby it 65 may be set and locked from a horizontal to a vertical position relative to the said base.

In testimony whereof I affix my signature.

ANDREW S. BROWN.
